Application March 26, 1947, Serial No. 737,276

2 Claims. (Cl. 40—36)

1

This invention relates to a machine for displaying rugs, and more particularly to a machine for mechanically laying out successively a large number of rugs so that each entire rug is presented to view.

Heretofore in displaying a number of rugs for merchandising and other purposes it has been necessary to exert a great deal of physical effort in unrolling or moving rugs by hand so that the successive rugs might be seen, and usually the services of two or more men are needed for this purpose. The natural tendency of a person displaying a number of rugs in rolls or piles is partially to unroll them or to thumb through the corners of rugs in a pile without separating the rugs so that only part of each rug is displayed. The advantage of displaying a rug so that the entire design may be seen is well known in the rug merchandising business. Space requirements in the average rug selling establishment do not permit a large selection of rugs to be laid out individually for display at the same time. To save space most of a stock of rugs must be kept in piles or rolls and handled by hand each time it is desired to display them to a customer. Furthermore the time consumed in laying out by hand a succession of rugs for display is a disadvantage.

We have now invented a machine which combines all the advantages of individual display of each entire rug in a large selection within limited space without the disadvantages above referred to.

Our principal object is to provide a machine which mechanically displays each of a large number of rugs in succession, so that the entire surface of each rug may be seen, all within limited space.

Essentially our invention comprises a shuttle which rotates to wind upon itself each rug from a pile of rugs and then traverses horizontally over the rug at the same time to pick it up without dragging it, continues its traverse with the wound up rug to a new location and automatically reverses its direction of rotation and traverse to lay the rug out flat in a second pile. The nature of the invention will best be understood from the following description in conjunction with the accompanying drawings, in which

Fig. 1 is a top plan view of the machine of the invention;

Fig. 2 is a view in elevation;

Fig. 3 is a fragmentary detail view in elevation;

Fig. 4 is a fragmentary end view partly in section taken along the lines 4—4 of Fig. 2;

2

Fig. 5 is a wiring diagram, and

Fig. 6 is a view in perspective of a shuttle clamp, flexible member and rug clip.

In the drawings a rectangular frame 10 made of tubular material such as pipe or metal tubing has vertical ladder-like sides 11 and 12. Longitudinal top members 13—13 and bottom members 14—14 are held in spaced relation vertically by upright braces 15—15. The sides 11 and 12 are held together top and bottom at the ends by cross braces 17—17. Horizontally to and inwardly of the top members 13—13 are additional longitudinal members 20—20 secured in spaced relation to the top members 13—13 by spacers 22—22. The members 20—20 serve as ways as will be explained hereinafter. The sides 11 and 12 of the frame 10 are braced in a vertical position by angularly disposed braces 24—24 (see Fig. 4) between the longitudinal members 20—20 and the bottom cross braces 17—17 at the ends of the frame 10. The various members of the frame 10 are secured together by welding and at its corners by pipe fittings.

A carriage 26 having side members 27—27 is mounted to travel in reciprocal directions along the ways 20—20 on grooved wheels 28—28 and it is held down on the ways by grooved wheels 30—30 under the ways 20—20. A pair of bicycle type driving chains 32—32 having double banked links 33—33 (see Fig. 4) are arranged one along each side of the frame 10 and looped over pairs of idler sprockets 34—34 which are located at the ends of the frame 10. The ends of each chain 32—32 on the top portions thereof are secured to bosses 36—36 on the side members 27—27 of the carriage 26. Consequently actuation of the chains 32—32 over the sprockets 34—34 moves the carriage 26 along its ways 20—20.

An electric driving motor 40 is mounted midway between the ends of the frame 10 upon a cross member 42 which is secured between the bottom longitudinal members 14—14 of the frame. The motor 40 turns a pulley 44 to drive a belt 46 and a pulley 48 on a shaft 50 of a gear box 52. The shaft 50 has a worm which turns a gear (neither being shown) which is mounted upon a driving shaft 54. The shaft 54 is journaled in upright members 56—56 which are secured to the frame 10. Fixedly mounted upon the shaft 54 near its outer ends are two sprockets 58—58 in such position that the top of each sprocket 58—58 engages the outer half of the lower portion of one of the double banked chains 32—32 to drive it. Extending inwardly from the upright members 56—56 are shoes 60—60 over

the outer halves of the driving chains 32-32 at the points where they are engaged by the sprockets 58-58. The shoes 60-60 are in sliding contact with the chains 32-32 and serve to maintain them in operative engagement with the sprockets 58-58 at all times. Energizing the motor 40 thus causes the carriage 26 to traverse along its ways, and reversing the motor reverses the direction of traverse.

A shuttle 62 in the form of a rectangular tubular frame is mounted upon a shaft 64 whose ends are rotatively journaled in the side members 27-27 of the carriage 26, so that the shuttle 62 may rotate about the axis of its shaft 64. The shuttle 62 is operatively connected to be rotated by the electric driving motor 40 cooperatively whenever the carriage 26 is traversed. Each of a pair of sprockets 66-66 on the carriage 26 is positioned to be engaged by the inner half of the lower portion of one of the driving chains 32-32 in contact with the bottom of each sprocket 66-66. The sprockets 66-66 are mounted upon stub shafts 68-68 which are journaled in the side members 27-27 of the carriage 26. The side members 27-27 carry shoes 70-70 depending therefrom which ride in sliding contact with and under the inner halves of the driving chains 32-32 at the points where they engage the sprockets 66-66. The shoes 70-70 maintain the driving chains 32-32 in operative engagement with the sprockets 66-66 at all times. On the inward ends of the stub shafts 68-68 are sprockets 72-72 which are operatively engaged to drive chains 74-74 which in turn drive idler sprockets 76-76. The idler sprockets 76-76 are operatively connected and mounted with sprockets 78-78 on stub shafts 80-80 which are journaled in the side members 27-27. The sprockets 78-78 in turn drive chains 82-82 and the latter turn sprockets 84-84 which are fixedly mounted upon the shaft 64 of the shuttle 62. Thus the shuttle 62 is rotated when the carriage 26 is traversed by the driving motor 40. As viewed in Figs. 2 and 3 when the carriage 26 is traversed to the left the shuttle 62 rotates counterclockwise. Reversing the motor 40 produces traverse to the right and clockwise rotation of the shuttle 62. The gear ratios are arranged so that the rate of movement of members 86-86 of the shuttle 62 circumferentially about its axis of rotation is substantially equal to the linear rate of traverse of the carriage 26, for reasons hereinafter explained.

A plurality of shuttle clamps 88-88 are adapted to clamp onto one of the members 86-86 of the shuttle 62 and each is connected by a flexible member 90 to a rug clip 92. (See Fig. 6.) Each shuttle clamp 88 is spring biased by a spring 94 to grip the shuttle member 86. The rug clips 92-92 are adapted and spring biased to grip the end edge of a rug.

When the machine of the invention is operated, a pile of rugs 94 is placed on a batt 96 within the right hand half of the frame 10 as viewed in Figs. 1, 2 and 3. The carriage 26 and shuttle 62 are placed at the right hand extreme of their traverse. Three rug clips 92-92 are attached to the right hand end of the rug 98 and the connected shuttle clamps 88-88 are clamped onto the lower member 86 of the shuttle 62. The number of rug clips 92-92 and shuttle clamps 88-88 used may be varied according to the size of the rugs to be displayed. The operator closes the switch 104 (described below), which energizes the electric motor 40 to traverse the carriage

26 to the left and to rotate the shuttle 62 counterclockwise. The rug 98 is thus wound around the shuttle 62 and the carriage 26 moves along over the rug 98 at a rate substantially equal to the rate of winding so that the rug 98 is rolled off the pile 94 without dragging it. When the carriage 26 passes over the left hand end of the rug pile 94 the rug has been completely wound around the shuttle 62. The shuttle 62 and carriage 26 continue to the left hand limit of traverse whereupon the motor 40 is reversed and the shuttle 62 starts to rotate clockwise. This starts to unwind the rug 98 and lay it out flat on the pile 100 of rugs on a batt 102 in the left hand half of the frame. The carriage 26 traverses to the right as the rug is laid down. The springs 94-94 in the shuttle clamps 88-88 have been adjusted in compression so that the clamps 88 grip the member 86 of the shuttle with just enough force to hold them while one turn of a rug is wound onto the shuttle at the beginning of the operation cycle. When the rug 98 is almost entirely laid out on the left hand pile 100 the shuttle 62 continues clockwise and to the right and pulls out of the clamps 88-88 which remain attached to the rug 98 by their clips 92-92 and returns to its starting position at the right hand extreme of its traverse ready to be attached to the next rug. Each new rug to be moved is attached to the shuttle 62 as above described after it has returned to its right hand position.

The electric motor 40 is electro-responsively controlled to complete the cycle of operation once a starting switch 104 is manually closed momentarily to energize it. In the schematic wiring diagram (Fig. 5) the carriage 26 is shown to the right in its starting position against the arm 105 of a normally closed limit switch 106 to hold it open. Having closed a main power switch 108 in a wire 110 from a main power source indicated by the plug 112 which has been plugged into a 110 volt power line, the circuit is now closed from the plug 112 through the wire 110 to a terminal 114 of the motor. To start the operation cycle, the starting switch 104 is momentarily closed by hand. The motor 40 is energized to traverse the carriage 26 to the left which allows the limit switch 106 to close so that the hand may be withdrawn from the starting switch 104. This circuit is completed from the plug 112 through a fuse 116, a wire 118, the switch 106, a wire 120, an arm 122 of a relay 124, a terminal 126, a wire 128, a normally closed limit switch 130, a wire 132, a wire 134, and a wire 136 to a terminal 138 of the motor 40. Current also passes from the wire 134 through an arm 140 of the relay 124, a terminal 142 and a wire 144 to a terminal 146 of the motor 40. A terminal 148 of the motor 40 is cross connected to a terminal 150 of the motor 40 through a wire 152, an arm 154 of the relay 124, a terminal 156 and a wire 158.

The carriage 126 continues to the left until almost at the limit of its traverse when it strikes the arm 129 of the limit switch 130 to break the circuit described above and shut off the motor 40. By inertia the carriage continues to the left until the motor almost stops. It has then struck the arm 159 of a normally open limit switch 160 to close it. This energizes the relay 124 to reverse the motor 40 and start traverse to the right by closing the circuit from the wire 120 through a wire 162, a wire 164, the switch 160, a wire 166, the relay 124 and a wire 168 to the wire 110,

When the relay 124 is energized, its arm 170 and the arms 122, 140 and 154 drop down onto their lower terminals. When the arm 170 makes contact with the terminal 172, a holding circuit to keep the relay energized after the carriage 26 leaves the switch 160 is established from the wire 162 across the arm 170 and through the terminal 172 to the relay and thence through the wire 168 to the wire 110. Current now flows to the motor to traverse the carriage 26 to the right from the wire 120 through the arm 122, a terminal 174, the wire 134 and the wire 136 into the terminal 138 of the motor. It also flows from the wire 134 across the arm 140, a terminal 176 and a wire 178 into the terminal 150 of the motor 40. The motor terminals 146 and 148 are cross connected through the wire 144, a terminal 180, the arm 154 and the wire 152.

The carriage 26 continues to the right until it strikes the arm of the limit switch 106, opens it and breaks the main circuit, whereupon the cycle is completed and the carriage comes to rest.

In displaying rugs with the machine of the invention it is only necessary for an operator to wheel a pile of rugs onto the batt with the aid of a dolly. His only remaining physical effort is to clip the end of each rug to the shuttle and the machine does the rest. The machine occupies little more space than two piles of rugs placed close together on a floor. It saves a great deal of labor, time and space.

We claim:

1. A machine for displaying rugs comprising in combination a frame, a pair of rug supporting platforms, one of which is arranged at one end of said frame and the other of which is arranged at the opposite end and on the same level as the first, mechanism for successively moving rugs from a pile of rugs in flat condition on one of said platforms and laying them out in a pile in flat condition on the other of said platforms, said mechanism including a pair of horizontal ways on said frame extending on one level between said platforms, a rotatable rug winding shuttle traversable reciprocally on one level back and forth on said ways between said platforms, power means operating to traverse said shuttle along said ways and at the same time to rotate it in

one direction and then at a predetermined point automatically to reverse its direction of traverse and rotation and means to connect the edge of a rug on one platform to said shuttle, whereby said rug is wound onto said shuttle as the latter moves from a first position toward the other platform and then unwound on its said other platform as the shuttle starts back toward its said first position.

10 2. A machine for displaying rugs comprising in combination a frame, a pair of rug supporting platforms, one of which is arranged at one end of said frame and the other of which is arranged at the opposite end and on the same level as the first, mechanism for successively moving rugs from a pile of rugs in flat condition on one of said platforms and laying them out in a pile in flat condition on the other of said platforms, said mechanism including a pair of horizontal ways 15 on said frame extending on one level between said platforms, a carriage traversable reciprocally on one level back and forth on said ways between said platforms, a rotatable rug winding shuttle mounted on said carriage, power means 20 operating to traverse said carriage along said ways from a first position and at the same time to rotate said shuttle in one direction and then at a predetermined point automatically to reverse the traverse of the carriage and also the 25 rotation of the shuttle, and means to connect the edge of a rug on one platform to said shuttle whereby said rug is wound onto said shuttle as the carriage moves from a first position toward the other platform and then unwound onto said 30 other platform as the carriage starts back toward its said first position.
